UNITED STATES PATENT OFFICE.

GEORGE BECK, OF ELDRED, NEW YORK, ASSIGNOR TO ENTERPRISE GAS STOVE MANUFACTURING COMPANY, OF NEW YORK, N. Y., A CORPORATION OF NEW YORK.

DESIGN FOR A RADIATOR-TOP.

SPECIFICATION forming part of Design No. 35,628, dated January 28, 1902.

Application filed December 31, 1901. Serial No. 87,968. Term of patent 7 years.

To all whom it may concern:

Be it known that I, GEORGE BECK, a citizen of the United States, and a resident of Eldred, Sullivan county, State of New York, have invented a certain new and useful Design for a Radiator-Top, of which the following is a specification.

The leading feature of my design consists in a radiator-top of substantially rectangular shape, having its edge portions bent downwardly and provided in its center with a series of oval ornaments surrounded by a chain of scrollwork which extends partly upon the curved edge portion.

Reference is to be had to the accompanying drawings, in which—

Figure 1 is a plan of a radiator top or plate embodying my design. Fig. 2 is a front view thereof, and Fig. 3 is a side or end view thereof.

A indicates oval ornaments disposed in a series lengthwise of the radiator-top and each containing ornaments B, somewhat of a fleur-de-lis character.

The radiator-top is substantially rectangular, with rounded corners, and the edge portions are bent down, forming convexed surface. The extreme edge portion is plain, as shown at C, and around the oval ornaments A is disposed a chain of scrolls D, each of which has a stem D', arranged approximately at a tangent to the adjacent oval ornaments A, and a leaf-like end D², which crosses said stem and terminates adjacent to one of the ornaments A. The stems D' are oppositely directed at each side of the longitudinal center of the radiator-top, and at the said center are located substantially circular ornaments or rosettes E. At the centers of the short sides of the rectangular radiator-top I arrange two oppositely-curved scrolls F.

I claim as my invention—

The design for a radiator-top substantially as shown and described.

GEORGE BECK.
